UNITED STATES PATENT OFFICE.

EDWARD RUTZ, OF CHICAGO, ILLINOIS.

FENCE-POST.

SPECIFICATION forming part of Letters Patent No. 296,070, dated April 1, 1884.

Application filed November 27, 1883. (No model.)

To all whom it may concern:

Be it known that I, EDWARD RUTZ, a citizen of the United States of America, residing at Chicago, in the county of Cook and State 5 of Illinois, have invented certain new and useful Improvements in Fence-Posts, of which the following is a specification, reference being had therein to the accompanying drawings.

10 My invention relates to an improved post. The object it has in view is to construct a post which will be strong and cheap, and in the manufacture of which no expensive or complicated machinery will be used.

15 To the accomplishment of the above the invention consists of the novel devices and combination of devices as will be described and claimed.

Reference will be made to the accompanying drawings, in which Figure 1 represents a section of fence in which my posts are used; Fig. 2, a vertical section through one of the posts; Fig. 3, a perspective of the same; Fig. 4, a section on line 1 1 of Fig. 2, and Fig. 5 a 25 similar view on line 2 2 of Fig. 2.

Like letters refer to like parts in each view. I form the post A of a single sheet of metal by bending such sheet to a triangular shape, with its edges nearly meeting, and I also prefer to have the post tapering, gradually growing larger from top to bottom. In one face of the post I cut notches a, in which the wires a' are inserted and held. At points near the lower end of the post, and in each of the three 35 faces thereof, I provide two openings, b b', situated one above the other. A metal strip, B, is passed through each of the openings b, and then through the corresponding opening, b', after which it enters the ground and serves

to hold the post securely in position. When 40 in position, the lower end of the post enters the ground for a few inches. The lower end of the post, from the ground-line upward a short distance, I fill with cement, or a block, 45 of wood, c, or other suitable material, is inserted therein, whereby greater strength and firmness are imparted to the post. The strips B, hereinbefore referred to as passed through the openings formed in the lower end of the post, are provided at their upper ends each 50 with an inwardly-projecting lug or head, d, which presses against the side of the post, and serves to bring the edges of the sheet from which said post is formed more closely together, and also to hold the cement or wooden 55 block c in position more securely.

What I claim is—

1. A hollow triangular post formed of a single sheet of metal, and provided near its lower end with suitable openings, in combination with metal strips passed through said openings, and provided with inwardly-projecting lugs or heads for forcing the edges of the metal sheet together, as set forth.

2. A hollow triangular post formed of a single sheet of metal, and having its lower end filled with suitable material, in combination with metal strips passed through openings in said post, and provided with inwardly-projecting lugs or heads for forcing the edges of the sheet together and holding the filling material in place, as set forth.

In testimony whereof I affix my signature in presence of two witnesses.

EDWARD RUTZ.
